TOILET APPLIANCE

William T. Dollar, Riverside, Calif.

Application May 28, 1941, Serial No. 395,651

12 Claims. (Cl. 132—84)

This invention relates to a novel appliance for bathrooms, and more particularly to an appliance for holding a drinking glass, toothbrushes, and tooth paste.

It is a primary aim of the invention to provide a holder of the character described of simple construction wherein the tooth paste holder and the toothbrush holders will combine with other parts of the appliance to form a recess for receiving a drinking glass.

It is a particular aim of the invention to provide a novel construction of paste tube holder and closure including hinged leaves which, when folded, will close the open neck of a paste tube and which, when extended, will expose the open neck of the paste tube so that the contents thereof may readily be dispensed therefrom.

Still another aim of the invention is to provide a paste tube holder having means for automatically returning the leaves thereof to folded positions to prevent the open neck of the paste tube being left exposed, and also provided with means for engaging tube necks of different diameters for adapting the holder for use with paste tubes of different sizes.

Still a further aim of the invention is to provide a toilet appliance wherein the toothbrush racks will engage the handle ends of toothbrushes for holding the bristles of the brushes in positions out of engagement with any surface which might collect dust or dirt.

Other objects and advantages of the invention will hereinafter become more fully apparent from the following description of the drawings, which illustrate preferred embodiments thereof, and wherein:

Figure 1 is a front elevational view of a preferred form of the invention.

Figure 2 is a side elevational view of the same.

Figure 3 is a top plan view of the same showing the paste tube holder and closure in an extended position.

Figure 4 is a transverse vertical sectional view taken substantially along the plane of the line 4—4 of Figure 1.

Figure 5 is a similar view taken substantially along the plane of the line 5—5 of Figure 3.

Figure 6 is a side elevational view of a modified form of the toilet appliance.

Figure 7 is a transverse vertical sectional view of the same taken substantially along the plane of the line 7—7 of Figure 6.

Figure 8 is a top plan view of another form of the invention.

Figure 9 is a side elevational view of the same,

Figure 10 is a longitudinal vertical sectional view, on an enlarged scale, taken substantially along the plane of the line 10—10 of Figure 8, and

Figure 11 is a perspective view of still another form of the invention.

Referring more particularly to the drawings, wherein like reference characters designate like or corresponding parts throughout the different views, 12 designates generally the toilet appliance as illustrated in Figures 1 to 5, and which includes a substantially flat horizontally disposed base 13, having an upturned rear end forming a flange or rear wall 14, which is provided with openings 15 for receiving fastenings, not shown, for mounting the appliance 12 on a vertical supporting surface such as a wall, not shown. The base member 13 is preferably formed of sheet metal, and is provided with extensions at its side edges 16 and 17, which extensions are bent to form socket portions 18 which project upwardly and outwardly relatively to the side edges 16 and 17, as best seen in Figure 1. The extensions forming the socket portions 18 also include the portions 19 which connect with and project outwardly from the edges 16 and 17, and which form abutments. Each of the sockets 18 is adapted to receive the handle end of a toothbrush, not shown, which handle ends rest on the abutments 19 so that the toothbrushes are supported thereby in upwardly and outwardly diverging relationship relatively to the base 13. It will thus be readily apparent that the sockets 18 and abutments 19 combine to form racks which detachably support toothbrushes so that the bristles of the brushes are held entirely out of engagement with any part of the appliance 12 and will thus be protected from contact with dirt or dust which might collect on the appliance 12.

The forward edge of the base 13, adjacent its edge 16, is split and rolled back to form spaced barrel portions 20. An elongated leaf or strip 21 of sheet metal is provided with transversely spaced barrel portions 22, at one end thereof. The adjacent ends of the barrel portions 22 are adapted to engage against the remote ends of the barrels 20 which are thereby disposed therebetween for receiving a hinge pin 23 which extends through the aligned barrels 20 and 22 to hingeably connect the leaf 21 to the base 13. A spring 24 is coiled about the pin 23, between the barrels 20 and has one end engaging against the upper side of the base 13 and its opposite end engaging against the side 25 of the leaf 21 to urge the

leaf 21 to a position at rest on the base 13, as illustrated in Figure 4. A leaf 26, which is likewise formed of sheet metal, is provided at one end thereof with barrels 27, corresponding to the barrels 22. The opposite end of the leaf 21 is provided with barrels 28, corresponding to the barrels 20, and said barrels 27 and 28 are adapted to be connected by a hinge pin 29. A spring 30 is arranged on the pin 29 between the barrels 28 and has one end bearing against the upper side of the leaf 26 and its opposite end bearing against the side of the leaf 21 opposite to its side 25 for causing the leaf 26 to rest in a superposed position on the leaf 21, as seen in Figures 2 and 4.

The forward edge of the base 13 is provided with an upset flange 31 which extends between the edge 17 and the barrels 22 and which combines with the leaves 21 and 26, the rear wall 14, and the sockets 18 which project from the edge 17 to form a drinking glass holding recess 32 in the base 13.

The leaf 26 is split longitudinally from its free end to intermediate of its ends, as seen at 33, and transversely, as seen at 34 (Fig. 4), at the inner end of the split portion 33 to form the corresponding portions 35 at the free end of the leaf 26. The adjacent edges of the portions 35 are provided with turned down portions 36 which are internally threaded to detachably engage the threaded neck 37 of a conventional paste tube 38, as indicated in dotted lines in Figures 1, 4 and 5. The leaf 26 is provided with upturned flanges 39 at its side edges and contiguous with the transverse slit 34 for reinforcing the leaf 26 at this, its weakest point. It will be readily apparent that the slit 33 and 34 provide means to permit the portions 35 to yield outwardly relatively to one another to permit the opening formed by the threaded portions 36 to be enlarged for engaging paste tube necks 37 of different diameters, to adapt the paste tube holder to conventional tubes 38 of different sizes.

The side 25, of leaf 21, constitutes the upper side of said leaf when it is in a folded position upon the base 13, and the leaf 21 is provided with a downwardly pressed socket portion adjacent the end thereof which is connected to the base 13, said socket portion 40 being arranged to receive the open end of the neck 37, when the leaves are folded, to prevent the contents of the tube 38 from leaking therefrom. The base 13 is provided with an opening 41 for receiving the recessed portion or socket 40 so that the leaf 21 can rest flat on the base 13, as best illustrated in Figure 4.

From the foregoing it will be obvious that an upward and outward movement of the tooth paste tube 38 relatively to the base 13 will move the leaves 21 and 26 from their positions, as seen in Figures 2 and 4, to their positions as seen in Figures 3 and 5, to expose the open end of the neck 37 so that the contents of the tube 38 can be dispensed therefrom downwardly and onto a brush disposed therebeneath, not shown. When the tube 38 is released the springs 24 and 30 will cause the leaves 21 and 26 to return to their positions, as seen in Figures 2 and 4, and it will be noted that the leaf 26 will support the tube 38 in an inverted position when the leaves are either folded or extended.

Another embodiment of the invention is illustrated in Figures 6 and 7, and which includes a substantially flat base 42, likewise formed of sheet metal and having extensions at the side edges thereof forming socket portions 18'. The

socket portions 18' are bent downwardly to form supporting legs for the appliance 12' to support the base 42 thereof in an elevated position, and said sockets are also adapted to support toothbrushes, not shown, by their handle ends, with the shelf, or other horizontal support 43 on which the appliance 12' is rested, forming stops for the lower ends of the sockets 18'.

A leaf 21' is hingedly attached to one end of the base 42, as indicated at 44, in the same manner that the leaf 21 is hingedly attached to the base 13. A second, upper leaf 45 is hingedly attached at one end thereof at 46 to the opposite end of the leaf 21', in the same manner that the leaf 26 is attached to the leaf 21. The leaf 45 is provided with an opening 47, adjacent its free end, which is sufficiently large to receive a large size paste tube neck 37. A socket member 48, of rubber or other yieldable material, is secured to the underside of the leaf 45 and is provided with an internally threaded bore 49, which registers with the opening 47, but which is smaller in diameter than said opening. It will be obvious that the socket member 48 will expand so that the opening 49 can be enlarged to detachably engage paste tube necks 37 of different diameters. The leaf 21' is provided with a downwardly pressed portion forming a socket 40', which functions for the same purpose as the socket 40, for sealing the open end of the paste tube neck 37 when the leaves 21' and 45 are in folded positions, as seen in full lines in Figure 6 and in Figure 7. The base 42 is provided with an opening 41' for receiving the socket 40'. It will be readily apparent that the leaves 21' and 45 can be extended, as seen in dotted lines in Figure 6, to permit the paste to be dispensed from the tube 38. In view of the detailed description of the appliance 12, a further description of the appliance 12' is deemed unnecessary.

Another embodiment of the invention is shown in Figures 8 to 10, designated generally 12a, and which includes a substantially flat supporting base 13a which is relatively thick and heavy and adapted to rest on a shelf or other horizontal support, not shown. The base 13a is provided with elongated openings 50, adjacent its side edges for engaging the handle ends of toothbrushes, not shown, for supporting the brushes in upright positions, and the support for the base 13a forms a stop to prevent the handle ends of the toothbrushes from sliding through the openings 50.

The toilet appliance 12a and paste tube holder 55 and closure includes a bottom leaf 51, an intermediate leaf 52, and a top leaf 53. The leaf 52 is attached, hingedly at one end thereof to an end of the leaf 51, as seen at 54, in the same manner that the leaf 21 is attached to the base 13, and the opposite end of the intermediate leaf 52 is hingedly attached at 55 to an end of the upper leaf 53, in the same manner that the leaf 26 is attached to the leaf 21. The top leaf 53 is provided with an opening 56, adjacent its free end, for engaging the neck 37 of a paste tube 38, and the intermediate leaf 52 is provided with a socket member 57, preferably of rubber, in which the open end of the neck 37 seats when the leaves are folded, as seen in Figures 9 and 10. The socket portion 57 prevents escape of the contents of the tube 38 while the leaves are folded, and also tends to force the contents which might have seeped out of the neck 37 back into the tube 38. The leaves 52 and 53 can be extended, as seen in dotted lines in Fig-

ure 9, for dispensing the paste from the tube 38. The bottom leaf 51 is swivelly attached to the upper side of the base 13a by a single fastening 58 so that the leaf 51 can be turned relatively to the base 13a for extending the leaves 52 and 53 in any direction from the base. The base 13a is adapted to be sufficiently heavy to maintain the appliance 12a in position on a supporting surface.

Another embodiment of the paste tube holder and closure only, is illustrated in Figure 11, and is designated generally 59. The holder and closure 59 comprises a bottom leaf 60, an intermediate leaf 61, and a top leaf 62, which leaves are preferably formed of rubber. The leaves 60, 61 and 62 are molded integral and are provided with reduced, flexible connecting portions 63 and 64, which are formed integral with the leaves. The connecting portion 63 connects the forward ends of the bottom leaf 60 and the intermediate leaf 61, and the connecting portion 64 connects the rear ends of the intermediate leaf 61 and the top leaf 62, said portions 63 and 64 forming hinge connections to permit the leaves 61 and 62 to open in the same manner as the leaves 21 and 26, 21' and 45, or 52 and 53. The upper leaf 62, adjacent its forward, free end, is provided with an internally threaded opening 65 for engaging the threaded neck of a tooth paste tube, not shown in Figure 11, in the same manner that the necks 37 of the tubes 38 are connected in the other embodiments of the invention. It will be readily apparent that the opening 65 can be expanded to adapt it to engage tube necks of different diameters, and as the leaves 60, 61 and 62 rest flush one upon the other, when folded, it will be readily apparent that the upper side of the intermediate leaf 61 will provide a closure for the open neck of the paste tube when the holder 59 is in a retracted, folded position, as illustrated in Figure 11.

In the embodiment of the invention shown in Figures 1 to 5, the leaf 26 folds flat upon the leaf 21 so that the depression 40 not only seals the open end of the neck but also combines with leaf 26 to form a dustproof closure around the entire neck 37. This same result is accomplished by leaf 45 and depression 40' in the holder 12' and by the leaf 53 and the socket member 57 in the holder 12a.

Various modifications and changes are contemplated and may obviously be resorted to as only preferred embodiments of the invention have been disclosed.

I claim as my invention:

1. A toilet device comprising a substantially flat base member having an upset rear wall, a leaf member hingedly connected at one of its ends to the upper side of the forward edge of said base member, and adjacent one side edge thereof, a second leaf member hingedly connected at one of its ends to the opposite end of said first leaf member, said leaf members being adapted to be disposed one above the other on the base, said upper leaf member being provided with means adjacent its free end for releasably engaging the neck of a paste tube for supporting the paste tube in an inverted position thereabove, the side edge of said base, remove to the side edge adjacent to which said leaf members are disposed, being provided with upwardly and outwardly projecting socket portions for engaging the handle ends of toothbrushes, said base member being provided with a front wall extending from adjacent said leaf members toward the

side edge thereof which is provided with said socket members, and said leaf members, front and rear walls and socket members combining to form a drinking glass holding recess in said base member.

2. A toilet appliance comprising a base member, socket members formed integral with opposite edges of said base member and projecting therefrom and disposed at angles thereto, said socket members being adapted to engage the handle ends of toothbrushes to provide toothbrush supporting racks, a leaf member hingedly connected at one end thereof to said base member and adapted to rest thereon, a second leaf member hingedly connected to the free edge of said first leaf member and superposed thereupon, and means formed in the free end of said second leaf member for detachably engaging the neck of a paste tube for supporting the paste tube thereon in an inverted position.

3. A toilet appliance as in claim 2, said socket members projecting downwardly from the base member and combining to form supporting legs for the appliance.

4. A paste tube holder and closure comprising a base member, a leaf hingedly connected at one end thereof to said base member and disposed thereon, a second leaf hingedly connected at one end thereof to the opposite end of said first leaf and disposed to rest thereupon, said second leaf being provided adjacent its free end with an opening for engaging the neck of a tooth paste tube for supporting the tooth paste tube in an inverted position, said first mentioned leaf forming a closure for the neck of the tooth paste tube when the leaves are resting one upon the other, and said leaves being movable relatively to one another and to the base for exposing the open end of the tooth paste tube.

5. A toilet appliance as in claim 4, said first mentioned leaf being provided with a depression arranged to project downwardly therefrom when said leaf is folded on the base, and said depression being arranged to receive the free end of the neck of the tooth paste tube when said leaves are folded one upon the other and upon the base.

6. A paste tube holder and closure as in claim 4, comprising spring means associated with said hinge connections for returning said leaves to folded positions on the base.

7. A paste tube holder and closure as in claim 4, said second leaf being formed of sheet metal, said second leaf being split longitudinally from intermediate of its ends to its free end and being provided with turned down portions forming an opening for engaging the neck of the tube, said turned down portions being internally threaded, said second leaf being split transversely at the inner end of said longitudinal split, and said slits combining to form yieldable portions at the free end of said second leaf to permit said turned down portions to be expanded for engaging tube necks of different diameters.

8. A paste tube holder and closure as in claim 4, said second leaf being formed of sheet metal, said second leaf being split longitudinally from intermediate of its ends to its free end and being provided with turned down portions forming an opening for engaging the neck of the tube, said turned down portions being internally threaded, said second leaf being split transversely at the inner end of said longitudinal split, said slits combining to form yieldable portions at the free end of said second leaf to permit said turned down portions to be expanded for engaging tube

necks of different diameters, and said second leaf being provided with upturned side edge portions, adjacent said transverse slit for reinforcing the second leaf at said point.

9. A paste tube holder and closure as in claim 4, comprising a member of yieldable material attached to the underside of said second leaf having a threaded bore extending therethrough and registering with the opening in the second leaf, said threaded bore being of a diameter less than that of the opening and being adapted to engage the threaded neck of the tube, and said member being yieldable so that the threaded bore can be expanded for engaging tube necks of different diameter.

10. A paste tube holder and closure comprising an upper, a lower and an intermediate leaf, said intermediate leaf being hingedly connected at its ends to ends of the upper and lower leaves so that said leaves can be folded one upon the other, said upper leaf being provided with means, adjacent its free end for engaging the neck of a tooth paste tube for supporting the tube in an inverted position and with its open end against the intermediate leaf, when the leaves are folded to provide a closure for the open end of the tube, said leaves being extensible for exposing the open end of the tube, and means for swivelly connecting the bottom leaf to a supporting surface.

11. A paste tube holder and closure comprising a bottom leaf, an intermediate leaf, and a top leaf, said leaves being formed of rubber, the

5 ends of said intermediate leaf being hingedly connected to opposite ends of the top and bottom leaves by integral restricted portions, and said top leaf being provided with an opening, adjacent its free end for detachably engaging the open neck of a paste tube for supporting the paste tube thereabove and in an inverted position.

12. A paste tube holder and closure comprising a base member, a leaf hingedly connected at one end thereof to said base member and disposed thereon, a second leaf hingedly connected at one end thereof to the opposite end of said first leaf and disposed to rest thereupon, said second leaf being provided adjacent its free end with an 10 opening for engaging the neck of a tooth paste tube for supporting the tooth paste tube in an inverted position, said first mentioned leaf forming a closure for the neck of the tooth paste tube when the leaves are resting one upon the other, 15 said leaves being movable relatively to one another and to the base for exposing the open end of the tooth paste tube, said first mentioned leaf being provided with a depression arranged to project downwardly therefrom when said leaf 20 is folded on the base, and said depression being arranged to receive and seal the open, free end of the tooth paste tube and to form a dustproof closure around the entire neck of the tube, when 25 said leaves are folded one upon the other and 30 upon the base.

WILLIAM T. DOLLAR.
